ATTORNEY.

UNITED STATES PATENT OFFICE

2,658,305

TETHERED TOY AIRPLANE CONTROL

Luther Hayes, Bellflower, Calif.

Application May 2, 1950, Serial No. 159,619

6 Claims. (Cl. 46—77)

1

My invention relates to improvements in toy airplane control, and particularly to a device for controlling power propelled toy airplanes in flight, and the objects of my invention are, first, to provide an arrangement and construction of a toy airplane control adapted to control effectively the flight of toy airplanes in windy weather; second, to afford facilities for the safeguarding of toy airplanes in flight by allowing automatically for adjustments to counteract dangerous wind pressure differentials; third, to provide effective means to control the tension of control lines between toy airplanes in flight and plane operators on the ground, and to prevent breaking of the control lines as well as damage to the toy airplane due to slack or excessive tension of the control lines; and fourth, to provide a simple and inexpensive control for toy airplanes in flight which may be adjusted for use on any power propelled toy airplane having two or more control lines extending from the plane operator on the ground to the toy airplane in the air.

Additional objects, together with further advantages derived in utilizing the present invention, will become apparent from the following detailed description thereof taken together with the accompanying drawing forming part of the specification, in which—

Figure 1 is a view in the perspective showing my control attached to a toy airplane;

Figure 2 is a plan view of my invention, attached to the tip of a toy airplane wing;

Figure 3 is a front elevational view of my invention attached to the tip of a toy airplane wing;

Figure 4 is a view in the perspective showing a modified form of my control attached to the tip of a toy airplane wing;

Figure 5 is a plan view of the control, shown in Fig. 4 in position to counteract a slack in the flight control lines between an operator and the toy airplane;

Figure 6 is a view in the perspective of a modified form of my control adjusted for use in windy weather;

Figure 7 is a view in the perspective of the control shown in Fig. 6 adjusted for use in windless weather.

Similar numerals refer to similar parts throughout the several views.

The toy airplane control illustrated in Figs. 1, 2, and 3 comprises a base 10, rigidly affixed to the wing tip of a toy airplane, an air deflecting shield 11, pivotally attached to said base 10, spring means 12 connecting the rear edge 13 of

5 the air deflecting shield 11, to the rear edge 14 of the base 10, and a guide line 15, extending from the front edge 16 of the air deflecting shield 11, to the toy plane control lines, 17 and 18 respectively, by means of a cross tie line 19.

The base 10, comprising a substantially rectangular plate 21, is rigidly fastened to the underside of the wing tip 22 of a toy airplane by means of a number of bolts 23, and a bolt plate 24, so as to extend partially beyond the wing tip 22 of the airplane. The free end of the base 10, is slotted horizontally, and the horizontal slot 25 carries the air deflecting shield 11 by means of a tongue 26, rigidly affixed to said shield, and pivotally attached to the base by means of pivot bolt 28 which extends through the base 10 and the tongue 26 at the approximate center of the horizontal slot 25.

A number of openings 27 is provided along 20 the rear edge 14 of the base 10.

The air deflecting shield 11 comprises an approximately oval-shaped body portion 29, having a slightly convex-shaped outer surface 31 and a flat inner surface 32. The front part 33 of the oval-shaped body portion 29 is flattened and the rear part 34 of the oval-shaped body portion 29 is pointed.

The oval-shaped body portion 29 is pivotally attached in a substantially vertical position to the base 10, by means of a flat strip 35, rigidly affixed longitudinally to the inner surface 32 of the oval-shaped body portion 29, and extending horizontally therefrom. The tongue 26 extends horizontally from the center of the flat strip 35, forming an integral part thereof, and is pivotally attached to the base 10, as described above.

The free end of the base 10 is slightly curved so as to permit the air deflecting shield 11 a rotating motion limited by the corners 37 and 38 respectively, of the free end 36 of the base 10.

A number of openings 39 are provided on the flat strip 35 between the front part 33 of the oval-shaped body portion 29 and the tongue 26. A number of openings 41 are also provided on the flat strip 35, between the tongue 26 and the rear part 34 of the oval-shaped body portion 29.

Spring means 12 are connected between one of the openings 41 to the rear of the tongue 26 and one of the openings 27 located along the rear edge 14 of the base 10.

The guide line 15 is connected between one of the openings 39 on the front part of the flat strip 35 and the cross tie line 19, hereinabove referred to.

In operation, the operator may start the engine

of the toy airplane. As the engine gains speed, the plane will lift off the ground and fly in a circular path, if the operator remains stationary, by holding the airplane control lines taut.

In the normal, or rest, position, the spring means 12 will pull the rear portion of the air deflecting shield 11 toward the plane, and in flight the air deflecting shield will act as an auxiliary rudder and pull the plane away from the operator, until the control lines are taut. At that point, the taut guide line 15 will counteract the action of the spring 12, and the air deflecting shield will move to an approximately parallel position to the fuselage, and remain in that position as long as all control lines remain taut.

If through a gust of wind or for some other reason the tension of the guide line 15 slackens, the action of the spring 12 will cause the air deflecting shield to move outwardly directing thereby the airplane outwardly and away from the operator automatically, and increasing thereby the tension in the guide line and control lines, until normal tension is re-established.

If through a gust of wind or for other reason, the airplane is forced in a direction away from the operator, the front end of the air deflecting shield will point inwardly, towards the operator, by reason of the action of the guide line 15, and the air deflecting shield will cause the airplane to return to its normal flying radius and will tend to decrease the tension in the guide lines and control lines.

Depending upon the respective openings used, the range of control and tension required to move the air deflecting shield can be adjusted for conditions of high wind velocities or for windless days respectively.

Once the airplane is in the air, the stabilizing action of the air deflecting shield will be automatic and safeguard the airplane which in many instances represents a considerable investment to the owner and, without the use of my invention, could be flown for safety's sake on windless or near windless days only. Without the use of my invention, a gust of wind might drive the plane toward the operator causing the lines to slacken and result in the loss of the uncontrolled plane.

The invention illustrated in Figs. 4 and 5 represents a modification of the air deflecting shield and uses a tubular-shaped body portion 43. All other parts in these figures are identical with those used in the construction shown in Figs. 1, 2, and 3, and thus this modification increases the range of possible adjustments.

The invention illustrated in Figs. 6 and 7 uses a pair of flat plates 44 and 45 respectively, of approximately rectangular shape, having slots 46 and 47 respectively, near one of the short edges 48, 49, 50 and 52 respectively.

A rectangular shaped back plate 53 is attached at a right angle to a flat strip 54 which is identical in construction with that used in the other embodiments of my invention. Screw holes near the ends of the rectangular shaped back plate 53 are so arranged as to permit screws 57 and 58 respectively, to pass through the slots in the respective plates and to cause the plates to be fastened in relatively fixed position to each other permitting thereby the adjustment of the surface exposed to the wind from a minimum area, as shown in Fig. 6, to a maximum area, as shown in Fig. 7 of the drawing.

The device illustrated in Figs. 6 and 7 may be pivotally attached to the base 10, by the same

means used in the other embodiments of my invention illustrated in the drawing, and the operation of the device is the same, as described above for the other embodiments of my invention.

While specific forms of my invention have been described, it is understood that the same may be modified without departing from the spirit of my invention.

I claim:

1. Apparatus of the character described for controlling the flight of a power propelled captive type U-control tethered toy airplane including a single base rigidly affixed to one wing tip of the airplane, one air deflecting member mounted pivotally in a vertical plane on only one wing and outside of the wing tip of the airplane on the base, spring means connecting the air deflecting member to the base on one side of the point of pivotal mounting of said air deflecting member, and a single guide line attached to the air deflecting member on the opposite side of the point of pivotal mounting of said air deflecting member and extending from it to an operating point outside of the airplane.

2. Apparatus of the character described for controlling the flight of a power propelled captive type U-control tethered toy airplane having wings and a movable control element including: one single air deflecting member mounted pivotally in a vertical plane on one wing only, spring means connected between the wing and the air deflecting member on one side of the point of pivotal mounting of said air deflecting member, and a single guide line connected to the air deflecting member on the opposite side of the point of pivotal mounting of said air deflecting member and extending from it to an operating point outside of the airplane.

3. Apparatus of the character described for controlling the flight of a power propelled captive type toy airplane having wings and a movable control element including: a base rigidly affixed to one wing; an air deflecting member mounted pivotally in substantially horizontal position on the base, said air deflecting member comprising a shield having an oval-shaped body portion with a convex-shaped outer surface and a flat inner surface; spring means connecting the air deflecting member to the base on one side of the point of pivotal mounting of said air deflecting member; and a single guide line attached to the air deflecting member on the opposite side of the point of pivotal mounting of said air deflecting member and extending from it to an operating point.

4. Apparatus of the character described for controlling the flight of a power propelled captive type toy airplane having wings and a movable control element including: a base rigidly affixed to one wing; an air deflecting member mounted pivotally in substantially horizontal position on the base, said air deflecting member comprising a tubular-shaped body portion, and a tongue rigidly affixed to the outside surface of the tubular-shaped body portion and pivotally connected to the base; spring means connecting the air deflecting member to the base on one side of the point of pivotal mounting of said air deflecting member; and a single guide line attached to the air deflecting member on the opposite side of the point of pivotal mounting of said air deflecting member and extending from it to an operating point.

5. Apparatus of the character described for controlling the flight of a power propelled captive

type U-control tethered toy airplane having wings and a movable control element including: a base rigidly affixed to one wing only; an air deflecting member mounted pivotally in a vertical plane on the base, said air deflecting member comprising a bracket, a pair of flat plates in fixed relation to each other and to the bracket, and means to adjust slidably the relative position of the plates to each other and to the bracket whereby the size of the air deflecting surface can be varied; spring means connecting the air deflecting member to the base on one side of the point of pivotal mounting of said air deflecting member; and a single guide line attached to the air deflecting member on the opposite side of the point of pivotal mounting of said air deflecting member and extending from it to an operating point.

6. Apparatus of the character described for controlling the flight of a power propelled captive type U-control tethered toy airplane having wings and a movable control element including: one single air deflecting member mounted piv-

totally in a vertical plane on one wing only, spring means connected between the wing and the air deflecting member on one side of the point of pivotal mounting of said air deflecting member, a single guide line connected to the air deflecting member on the opposite side of the point of pivotal mounting of the air deflecting member and extending from it to an operating point outside of the airplane, and means adapted to adjust the tension of the spring means relative to the tension of the single guide line.
